UNITED STATES PATENT OFFICE

EMBURY MCLEAN, OF NEW YORK, N. Y.

FAN-BLOWER.

1,056,813.

Specification of Letters Patent. Patented Mar. 25, 1913.

Application filed July 10, 1907. Serial No. 383,063.

To all whom it may concern:

Be it known that I, EMBURY MCLEAN, a citizen of the United States, and a resident of the city of New York, borough of Brooklyn, in the county of Kings and State of New York, have invented certain new and useful Improvements in Fan-Blowers, of which the following is a specification.

This invention relates to fan blowers and 10 has particular application to a type of blower combining and embracing certain advantageous features of a volume blower and a pressure blower.

As is well known, there are two general 15 types of fan blowers, namely, volume blowers and pressure blowers. The general distinction between the two types is that the clearance between the scroll and the wheel in the volume blower is much greater than 20 in the pressure blower.

The improvement to which the present invention relates is directed toward combining with the type of scroll used for a volume blower, a restricted space at the point of 25 cut-off, so that the blower will handle a large volume of air similar to the ordinary type of volume blower, and will be able to develop an increased pressure, due to an increase in resistance at the outlet to a greater 30 extent than would be obtained with an ordinary blower. In practice, if desired, I may also have this restricted space which controls the point of cut-off or minimum distance between the housing and the periphery of the 35 wheel, adjustable, so that it may be varied to suit any given conditions under which it is required to operate and give the most efficient results for those conditions.

The invention consists in the construction, 40 combination and arrangement of parts set forth in and falling within the scope of the appended claims.

In the accompanying drawings wherein I have shown a preferred embodiment of my 45 invention, Figure 1 is a vertical sectional view taken through a blower embodying my improvements; the dotted lines showing the scroll of the ordinary pressure blower, and the full lines of the housing illustrating and 50 following the course of the ordinary volume scroll as far as the point A', where it departs from such scroll and is brought inward close to the periphery of the wheel forming a contracted space or throat between the 55 housing and the wheel at the point of cut-off; Fig. 2 is a similar view showing the

housing or scroll adjustable at the point of cut-off, and this adjustable portion may be clamped in any desired position of adjustment, or its position may be varied and controlled automatically. 60

One of the aims and purposes of my invention is to provide a blower having the ability to develop pressure in proportion to the resistance at the outlet and at the same time possess the advantageous features of simplicity, economy of operation and capacity of the centrifugal volume blower. It accomplishes these results to a greater extent than the ordinary centrifugal fan blower 65 and, within the limits in which it is intended to be used, as, for example, for furnace work, it approaches the results obtained by a displacement blower. In the latter the volume of air supply varies with the speed, and the 70 pressure at which the air is supplied varies with the resistance. 75

When my invention is used to supply air to a furnace the speed of the blower will control the volume of air supplied and the 80 rate of combustion, and the pressure at which the air would be supplied would be dependent upon the character of the fire being maintained, and the thickness of the bed of fuel. 85

Referring now to the accompanying drawings in detail, V designates a blower comprising a housing H and a wheel or fan F revolving therein and mounted in any suitable manner. In the full lines shown in Fig. 90 1, I have shown the housing form or scroll of a volume blower, which volume scroll extends from the point A to the point A'. At the point A' it departs from the ordinary scroll of the volume blower and the 95 remainder of its distance, or, as far as the point A' it approaches the periphery of the fan wheel and reduces the cut-off space which ordinarily exists in a volume blower. My device thereby partakes of the function and 100 nature of a pressure blower at the throat portion, so that an increase in the resistance at the outlet D will develop an increased pressure similar to that of a regular pressure blower. 105

In Fig. 2 I have shown a construction wherein the wall of the casing or housing, indicated at E, is rendered adjustable by the hinge or pivot P. The horizontal portion E' of the movable wall lies above or 110 overlaps the outlet or discharge duct of the blower and is slidable thereon and may be

held in any adjustable position by means of the screw S. It will be seen that the arrangement of the part E is such that throughout its movement in accomplishing its intended purpose, it in no way restricts or reduces the area of the outlet duct from the casing, so that the volume of air delivered from the blower is not affected by the movement of said part E. K is a governor having connecting rods c, c' and c² connected with the slide T, so that the amount of opening at the throat of the blower may be automatically regulated according to the speed of the blower.

15 Having thus described my invention, what I claim is:

1. A fan blower having the proportions of wheel and form of scroll of a volume blower, and an adjustable restricted space 20 at the point of cut-off relatively less than that of a volume blower and means for automatically adjusting the area of said restricted space in proportion to the speed of revolution of the wheel.
- 25 2. A blower provided with an adjustable throat section, and means for automatically controlling the space between the wheel and the housing at the point of cut-off.
3. The combination with a blower of 30 means for automatically controlling the space between the wheel and the housing at the point of cut-off.
4. A fan blower having a scroll casing and impeller wheel of the form and relative 35 arrangement of a volume blower, the casing being provided with an exhaust duct tangential to the impeller wheel, and the peripheral wall of the scroll casing connected to the exhaust at the point of cut-off being

movable toward and away from the periphery of the impeller wheel, said movable part being so curved that the general scroll form of the casing may be maintained at different points to which said movable wall may be moved, and said movable part being 45 so arranged that throughout its movement the area of the exhaust duct is not varied.

5. A fan blower having a scroll casing and impeller wheel of the form and relative arrangement of a volume blower, the casing 50 having an exhaust duct tangential to the impeller wheel and a portion of the peripheral wall of the scroll casing connected to the exhaust duct at the point of cut-off being hingedly connected to the body of the 55 scroll casing and movable toward and away from the periphery of the impeller wheel.

6. A fan blower having a scroll casing and impeller wheel of the form and relative arrangement of a volume blower, the casing 60 having an exhaust duct tangential to the impeller wheel and a portion of the peripheral wall of the scroll casing connected to the exhaust duct at the point of cut-off being hingedly connected to the body of the 65 scroll casing and having an extended slideable portion, and means associated with said slideable portion for adjustably locating said hinged part relative to the periphery of the impeller wheel.

In testimony whereof I have hereunto signed my name in the presence of two subscribing witnesses.

EMBURY McLEAN.
